UNITED STATES PATENT OFFICE.

KARL WIESER, OF BREDENEY, GERMANY, ASSIGNOR TO FRIED. KRUPP AKTIENGESELLSCHAFT, OF ESSEN-ON-THE-RUHR, GERMANY.

PROJECTILE WITH VISIBLE TRAJECTORY.

1,075,391.

Specification of Letters Patent. Patented Oct. 14, 1913.

Application filed January 25, 1913. Serial No. 744,224.

To all whom it may concern:

Be it known that I, KARL WIESER, residing at Bredeney, Germany, a subject of the Emperor of Germany, have invented a certain new and useful Improvement in Projectiles with Visible Trajectories, of which the following is a specification.

This invention relates to projectiles, the trajectory of which is made visible by means of a charge, such as for instance, a smoke producing charge.

One embodiment of the invention is represented in the drawing, wherein—

Figure 1 shows a longitudinal section partly in side elevation of a portion of a projectile and Fig. 2 a top plan view of Fig. 1.

The point of the projectile is designated by letter A, and B is a housing mounted thereon which housing comprises a slightly conical part b¹, a top b² and base b³. The base b³ is shaped to conform with the point of the projectile and riveted to the flange b⁴ of the portion b¹. A fuse C is built in to the top b², and this fuse is constructed in well known manner, so that it operates in firing the projectile. The fuse is intended to ignite a smoke producing charge D enclosed by the housing B. In order to permit the flame from the smoke producing charge to be emitted from the housing B orifices b⁵ are provided in the parts b¹, b² of the housing.

The connection between the housing B with the projectile is accomplished by a bayonet lock, which comprises a plurality of L-shaped slits b⁶ cut in the flange b⁴ and the base b³, and by screws a¹ threaded in the point of the projectile.

In firing the projectile the fuse C is put in action and ignites the smoke producing charge D. The smoke arising from the combustion of the smoke producing charge is emitted through the orifices b⁵, which makes the trajectory of the projectile visible, so that the position of the trajectory relative to the target may be observed.

The easily detachable connection of the

housing B with the projectile possesses the advantage, that the projectile may be fired as required with or without the smoke producing charge.

In order to make it possible to fire projectiles provided with smoke producing charge and projectiles without smoke producing charge from the same gun, one directly after the other, without having to resort to other tables and the change in the sight; the housing B has been provided with such external shape that the projectile will follow approximately the same trajectory with the same elevation of the gun and with the same propelling charge, whether it carries smoke producing charge or not. This result is made possible through the slender shape of the housing B, whereby the projectile fired with a smoke producing charge will experience less air resistance than a projectile without a smoke producing charge. The influence on the muzzle velocity and the consequent influence on the trajectory of the projectile, of the increased weight of the projectile, caused by the housing carrying the smoke producing charge, is almost counteracted by the diminished air resistance.

I claim:

1. In a projectile carrying a charge for tracing its trajectory; a housing for said charge constructed to be easily detachable from the point of the projectile; the external shape of said housing being such, that the trajectory will remain practically unchanged if the projectile is fired with or without said charge from a gun with the identical propelling charge and the same elevation.

2. In a projectile carrying a smoke producing charge for tracing its trajectory; a housing for said charge comprising a base conforming in shape to the point of the projectile, a body slightly tapered forward and orifices in the side of said body to emit the smoke from the burning charge fixedly attached to said base and a top carrying a fuse; L-shaped slits in the housing

and studs in the point of the projectile registering with said slits for easily detaching the housing from the projectile; the shape of said housing being such that the trajectory will be practically unchanged, under otherwise similar firing conditions, whether the projectile carries the housing or not.

The foregoing specification is signed at Barmen, Germany, this 4th day of January, 1913.

KARL WIESER. [L. S.]

In presence of—

ALBERT NUFER,

ADOLF HALDEWUNG.
